UNITED STATES PATENT OFFICE.

EMILE LECUYER, OF SALINA, KANSAS.

HARNESS-PAD.

No. 863,542.

Specification of Letters Patent.

Patented Aug. 13, 1907.

Application filed February 2, 1907. Serial No. 355,461.

To all whom it may concern:

Be it known that I, EMILE LECUYER, a citizen of the United States, residing at Salina, in the county of Saline and State of Kansas, have invented certain new and 5 useful Improvements in Harness-Pads, of which the following is a specification.

My invention relates to improvements in harness pads.

Its objects are principally to dispense with the use of 10 nuts or burs to aid in connecting together of the pads and the tree; to provide for the ready application of the pad-tree to any kind or pattern of pad; to also provide for the use of any form of pad-skirt also without the aid of burs or nuts as in the application of the pad-tree 15 aforesaid; and to carry out these objects in a simple, expeditious and effective manner.

Said invention consists of certain features or instrumentalities substantially as hereinafter fully disclosed and specifically pointed out by the claims.

20 In the accompanying drawing illustrating the preferred embodiment of my invention—Figure 1 is a perspective view thereof. Fig. 2 is a vertical longitudinal section of the same. Fig. 3 is a transverse section produced through the line of separation between the sections 25 of a pad-tree member. Fig. 4 is a disassembled perspective view of the pad-tree plate-clamp and one-half of the yoke or link uniting the opposite plate-clamps of the two members or halves of a complete 30 pad-tree. Figs. 5 and 6 are like views of the two sections of a pad-tree member, respectively.

In the disclosure of my invention, I form each pad-tree member 1 of two sections or halves, the lower being designated as 2 and the upper, as 3, and provide each half or section with an interiorly screw-threaded half-sleeve 4 projecting from both the inner and outer surfaces of said pad-member sections or halves, the inner projecting portions of said half-sleeves being let into a circular orifice 5 produced in the outer leather portion of the pad 6. The lower section or half has at one end 35 upon its inner surface an upward pointed or extending hooked projection 7, taking into an aperture 8 in the leather-portion of the pad for the retention of that end of the latter thereon. Said section or half 2 has also upon its outer surface preferably two outstanding 40 straight studs 9, 10, one preferably longer than the other, for insertion through, and connecting together, one upon the other, the portions of the pad-skirt 11 and for the retention of the latter in place. The upper pad-tree section 3 has projecting, from the inner surfaces of 45 50 55 60 65 70 75 80 85 90 95 100

per end, two downward-pointed or extending hooked projections 14 effective for entering or engaging apertures 15 produced in the inner leather covering of the pad, for securing the corresponding end of the pad thereon.

55

Overlying the pad-tree member of the sectional construction above described, is a plate or clamp 16 having apertures *a*, *a*, receiving the ends of the studs 9, 10 aforesaid, and an orifice 17 therein, with an upraised surrounding extension or collar 18 formed upon said 60 plate or clamp, and through which orifice passes the outer portions of the half-sleeves 4 and which plate provides for the retention of said half-sleeves in effective relation one to the other, as the screw-threaded shank-portion of the line or rein receiving terret 19 is screwed, 65 as it is, into said half-sleeves and whereby the sections of the pad-tree member are effectively held in fixed relative position and to the pad. A yoke or link-member 20, only one half of which is disclosed is adapted to be secured in place by the screw-threaded shank of the 70 check-rein or "water" hook (not shown), said shank passing through said link or yoke at 21. To said link or yoke is connected the overlying clamp-plate of each pad-tree member, each clamp-plate having its upper end formed into a narrow extension as at 22, which extension is bent to form a right-angle as at 23. Said extension has its extreme upper terminal portion initially inserted through a transverse slot 24 in the yoke or link 20 and its said right-angled bend subsequently dropped into said slot while said terminal portion is itself finally 75 dropped into a second like slot 25 formed in the upper section 3 of the pad-tree member, near its upper end, thus providing for the intimate interlocking of all of these parts.

As before noted, it will be observed that the use of all 85 nuts or burs for aiding the effective retention of the parts in place is completely obviated, both as to the attachment of the pad-tree to the pads and to the pad-skirts, while the parts are all quickly and effectively assembled and the pad-tree is adapted to be applied to 90 any kind or pattern of pad desired.

I claim—

1. A harness-pad tree-member comprising two sections provided with interiorly screw-threaded half-sleeves and with means for their attachment to a pad, screw-thread 95 equipped means for engagement with said half-sleeves and means for the retention of said half-sleeves in effective relation with said screw-thread equipped means.

2. A harness-pad tree-member comprising two sections provided with interiorly screw-threaded half-sleeves and 100 hooked projections effective for their attachment to a pad,

- and screw-thread equipped means for engagement with said half-sleeves and means for the retention of said half-sleeves and said screw-thread equipped means in effective relation one with the other.
- 5 3. A harness-pad tree-member comprising two sections provided with interiorly screw-threaded half-sleeves and with means for their attachment to a pad, screw-thread equipped means for engagement with said half-sleeves, a plate for the retention of said half-sleeves in effective 10 relation with said screw-thread equipped means, and a

yoke having a slot, said plate having an upper end extension, and one of said sections of said pad-tree member also having a slot, said plate-extension adapted to engage said slots.

In testimony whereof I affix my signature, in presence 15 of two witnesses.

EMILE LECUYER.
